FIG. 4.

FIG. 5.

UNITED STATES PATENT OFFICE.

OSCAR JOHNSON, OF CHICAGO, ILLINOIS.

ELECTRIC SWITCH.

1,233,364.

Specification of Letters Patent. Patented July 17, 1917.

Original application filed January 27, 1913, Serial No. 744,304. Divided and this application filed July 5, 1913. Serial No. 777,381.

To all whom it may concern:

Be it known that I, OSCAR JOHNSON, a citizen of the United States, residing at Chicago, in the county of Cook and State of Illinois, have invented certain new and useful Improvements in Electric Switches, of which the following is a specification.

This application is in the nature of a division of my application Serial No. 744,304, filed January 27, 1913, which earlier application discloses means for controlling electrically-propelled vehicles such as street and interurban cars. One of the objects of the invention disclosed in said earlier application is to provide means whereby the motor circuit may be opened by the conductor or a passenger, and whereby the motor circuit is automatically opened whenever the motorman operates the motorman's brake valve to apply the brakes. The devices for opening and closing the motor circuit are described and claimed in the present application.

In the accompanying drawings, Figure 1 is an elevation of the circuit opener and closer. Fig. 2 is a top plan view thereof. Fig. 3 is a vertical sectional view through the circuit opener and closer taken in the plane of dotted line 3 3 of Fig. 5. Fig. 4 is a vertical sectional view taken in the plane 30 of dotted line 4 4 of Fig. 5. Fig. 5 is a view taken in the plane of dotted line 5 5 of Fig 4. Fig. 6 is a sectional detail view. Figs. 7 and 8 are views of the electrical contacts. Fig. 9 is a view of a means for locking the circuit opener and closer in open position.

In the present embodiment of the invention, the switch comprises a casing 20 having a cover 20^a. On two parallel guide rods 25 fixed in the casing is mounted a slide 26. A rod 22 is supported in the casing 20 for longitudinal reciprocating movement by means of a bearing 23 and a fixed tubular guide 24 in the casing. The rod 22 extends freely through an opening 26^a (Fig. 3) in the slide 26, and is provided with an annular shoulder or collar 22^a. Coiled springs 28 surrounding the guide rods 25 tend to hold the slide 26 in the closed-circuit position. On opposite sides of the slide 26 are pivots 26^b (Fig. 3) upon which are rotatably mounted two electric contacts 27. These contacts are slidably insulated from the pivots and the slide. A bridge 26^c is secured to the slide 26 by means of screws 26^d, and is insulated from the slide by

means of insulating pieces of fiber or the like and by several loose strips of mica 26^e. The bridge 26^c carries two contacts 26^f that continually engage the contacts 27.

The contacts 27 are arranged to engage other contacts 21^a herein shown as having the form of sleeves mounted upon posts 21, said posts being secured to but insulated from the casing 20. The posts 21 are connected to binding posts 21^b and 21^c to which the wires comprised in the motor circuit are connected. M (Fig. 4) indicates the car-propelling motor. As stated, the contacts 21^a are in the form of sleeves mounted for rotation upon the posts 21. The sleeves are held in position by means of a pin 51 fixed in the post and engaging within recesses 52 in the lower end of the sleeve. In case the sleeves become carbonized or otherwise damaged they may be lifted off, turned one third of the way around, and replaced, a new contact surface being thus provided.

The contacts 27 likewise are movable to present new contact surfaces. As stated, the contacts 27 are mounted for rotation, and each is provided with a plurality of facets 27^a adapted to contact with the periphery of one of the sleeves 21^a. It will be seen that the contacts 27 may be turned upon their pivots to present new surfaces for engagement with the sleeves 21^a. The bridge 26^c is sufficiently resilient to permit the contacts 27 to be turned. Normally, the springs 28 hold the contacts 27 in electrical engagement with the contacts 21^a.

Attached to the casing 20 is a cylinder 29 within which is a piston 30 (Fig. 4) fixed upon the rod 22. One end of the cylinder is connected to an air supply pipe 7 by means of a pipe 31. When air is admitted through the pipe 31 the piston is forced in the direction to carry the collar 22^a against the slide 26 and thus move the contacts 27 away from the contacts 21^a, thereby opening the motor circuit.

A coiled spring 33 (Fig. 4) surrounding the rod 22, and interposed between the end of the guide 24 and an annular shoulder 22^b on said rod, serves to move the piston 30 into normal position when the air pressure is removed from said piston, that is to say, when the pressure has been exhausted from the train line.

When the circuit-breaker is operated to open said circuit, it is locked in the open po-

100

105

110

sition until the motorman is ready to operate the controller to start the car. The means herein shown for thus locking the circuit-breaker comprises a dog 34 (Fig. 9) pivoted 5 between its ends at 35. To one end of said dog is pivoted a stem 36 to which is attached the armature (not shown) of an electro-magnet 38. When the slide 26 is moved by the piston 30 until said slide has passed the dog 10 34, said dog tilts into position to obstruct the return of the slide. Any suitable means may be employed for releasing the dog, preferably some means actuated in the rotation of the speed roll of the controller located on 15 each platform, said controller being connected directly with the trolley (not shown). Such controller-actuated releasing means may be of any suitable character. Herein I have shown electrical releasing means, said 20 means comprising coating contacts in the controller α (Fig. 1), 39 being a stationary contact finger, and 39^a being a contact on the speed roll. The finger 39 is connected to the portion of the circuit including the trolley, 25 by means of a wire 39^b, while the contact 39^a is connected to one terminal of the electro-magnet by means of a wire 39^c. The other terminal of the magnet may be connected to ground, as shown. The contacts 39 and 39^a 30 are so arranged in the controller that as the controller handle leaves the "off" position, a circuit is closed through the electro-magnet, whereupon the latter raises the armature and thereby withdraws the dog 34 from locking 35 relation to the slide 26. The latter is then moved into closed position by the springs 28, provided the motorman has set the motorman's brake valve at release. So long as there is pressure in the train line, the circuit- 40 breaker cannot be closed; thus it is impossible to supply current to the motor while the brakes are on.

If desired, suitable means such as a valve 43 controlled by the piston 30 may be provided to connect the sand trap 62 to the air supply pipe 44 when the circuit-breaker is operated. The outlet side of the valve 43 communicates with the sand trap through a pipe 42.

50 The casing 20 may be filled with oil or other suitable liquid to lubricate the moving parts.

After a stop has been made and it is desired to set the car in motion, the motorman 55 turns the motorman's brake valve to full release, whereupon the air in the brake cylinder and the train line is exhausted in the usual manner. The spring 33 then restores the rod 22. As soon as the controller α is 60 operated, the contact 39 closes a circuit

through the electro-magnet 38, thus causing the slide 26 to be unlocked, whereupon the springs 28 move the slide to close the motor circuit.

I claim as my invention:

1. In an electrically-propelled vehicle, the combination of a motor-circuit breaker, pressure-fluid means for opening said circuit breaker, means for locking the circuit-breaker in open position, a motor controller, and means operable by said controller for operating said locking means to release the circuit-breaker. 65

2. In an electrically-propelled vehicle, the combination of a motor-circuit breaker; 70 means for opening the circuit breaker; means for locking the circuit-breaker in open position; a motor-controller comprising a speed roll; and means operable by said speed roll for operating said locking means to release the circuit-breaker. 75

3. In an electrically propelled vehicle, the combination of a motor circuit-breaker, means tending to close the circuit-breaker, pressure-fluid means for opening said circuit-breaker against the force of the closing means, means for locking the circuit-breaker in open position, a motor controller, and means governed by said controller for operating the locking means to release the circuit-breaker. 80

4. In an electrically propelled vehicle, the combination of a motor circuit-breaker, means tending to close the circuit-breaker, means for opening the circuit-breaker against 85 the force of the closing means, a detent for locking the circuit-breaker in open position, an electro-magnet for withdrawing the detent, a circuit in which said electro-magnet is included, and a motor controller for closing said circuit. 90

5. An electrically-propelled vehicle having, in combination, a car-propelling motor, and a circuit therefor, a breaker included in said circuit, means for closing and maintaining said circuit breaker in closed position, means for operating said circuit-breaker to open the circuit, means for locking the circuit-breaker when in open position, a motor controller, and means operable by said controller for operating said locking means to release the circuit-breaker whereby said closing and maintaining means is enabled to close said circuit-breaker. 105

In testimony whereof I affix my signature 110 in presence of two witnesses.

OSCAR JOHNSON.
